UNITED STATES PATENT OFFICE

105,770

DESIGN FOR A TRIANGULAR FEATHER

Joseph Abrams, New York, N. Y.

Application July 17, 1937, Serial No. 70,509

Term of patent 3½ years

To all whom it may concern:

Be it known that I, Joseph Abrams, a citizen of the United States of America, residing in the city of New York, county of New York, and State of New York, have invented a new, original, and ornamental Design for a Triangular Feather, of which the following is a specification, reference being had to the accompanying drawing, forming part thereof.

Figures 1 and 2 are perspective views showing two sides of my triangular feather.

Fig. 3 is a bottom view thereof.

My design is characterized by the tricolors on the triangular feather as shown.

I claim:

The ornamental design for a triangular feather as shown and described.

JOSEPH ABRAMS.
